UNITED STATES PATENT OFFICE

2,268,691

ELECTRICALLY HEATED FURNACE

Frank W. Brooke, Pittsburgh, Pa., assignor to
 Swindell-Dressler Corporation, Pittsburgh, Pa.,
 a corporation of Pennsylvania

Application March 20, 1939, Serial No. 262,860

10 Claims.

(Cl. 13—20)

The general object of the present invention is to provide an electrical heated furnace, and particularly a metallurgical furnace, adapted for use under conditions requiring a relatively high temperature and high furnace heat supply rates, and making it highly important to maintain a furnace chamber atmosphere which is non-oxidizing. There is need for such a furnace, for example, in the production of so-called oxygen-free copper, by a process in which copper is melted and refined in a furnace chamber in which a reducing atmosphere is maintained.

A specific object of the present invention is to provide furnace heating means comprising hollow porous electric resistors of refractory material, such as silicon carbide, Alundum, chromite, and carbon in amorphous, semiamorphous or graphitic forms, and to maintain said resistors in operative condition and to control atmospheric conditions within the furnace chamber, by continuously passing into the hollow resistors a reducing gas including a carbon constituent which will crack at high temperatures, whereby the joints or cracks in the resistor are sealed by carbon cracked out of said gas and depositing in said joints or cracks, and whereby there is a continuous movement of the gas into the furnace chamber through the resistor pores. The gas thus entering the furnace chamber has a tendency to maintain a general furnace chamber atmosphere of a reducing character, and maintaining a reducing gas envelope about each resistor.

A specific object of the present invention is to provide for the use in a furnace of electrical heating elements comprising heating resistors in the form of such cylinders of amorphous or semiamorphous carbon, varying in diameter from six inches to 24 inches or so, and ranging in length up to 72 inches, as are now commercially available in large quantities, and at a relatively low cost, for use as the electrodes of electric arc furnaces, employed for various metallurgical purposes.

A more specific object of the present invention is to provide simple and effective means for supporting the carbon resistors, and for passing the required relatively large currents required through the resistors without giving rise to undesirably high heat losses at the ends of the resistors.

In the preferred form of the present invention, the heating resistors formed of carbon in an amorphous or semi-amorphous form, have their ends mechanically connected to bodies of graphite which have a specific resistance much

lower than that of the electrode material, and which are mounted in opposing walls of the furnace, and have their outer ends attached to metallic contact or terminal members, which may be artificially cooled, if necessary, to keep them from attaining injuriously high temperatures; and each heating element is formed with a longitudinal gas passage or space extending through the carbon resistor body and graphite end members of the heating element, and means are provided for passing a suitable gas into said space under a pressure sufficient to create an outflow of gas through cracks and joints of the heater element structure, and through the pores of the carbon and graphite portions of the element.

Carbon is ordinarily "cracked" out of the gas entering the cracks and joints, so as to seal the latter, quite rapidly, in consequence of the relatively high temperatures to which the cracks and joint walls are subjected as a result of the relatively high crack and joint resistance to electric current flow. The carbon thus deposited in element cracks and joints, not only closes and seals the cracks and joints, but provides a good mechanical and electrical bond between the crack or joint walls.

The major sealing action is effected during an initial operating period, ordinarily of a few hours or days duration and while the composition of the gas employed during that period may be the same as that supplied in subsequent regular operation, I consider it generally desirable to effect the major sealing action by means of a gas such as propane from which carbon may be liberated by a cracking action more freely than from a more stable, less expensive and more easily obtainable reducing gas which may be supplied for flow through the carbon and graphite pores of the heating element in regular operation.

Initially, the pore or void space in the carbon and graphite bodies of the improved heating element, amounts to 20 or 30 per cent of the overall volume of said bodies. While in use, the pores tend to fill up with deposited carbon, cracked out of the gas, the rate at which carbon may ordinarily be expected to deposit in the pores, is not high enough to prevent the heating elements from having an effective operating life of commercially acceptable length, and much longer than they would normally have but for the reducing gas flow through their carbon and graphite pores.

A further specific object of the invention is to connect the resistance body end members and metallic contact or terminal members of each

heating element by threaded joints and to associate therewith a torsion device by which the joints can be kept tight, notwithstanding the joint loosening tendency of heating element temperature changes. Such a torsion device may comprise means for subjecting one end of the heating element to the torque produced by a weight or a spring suitably connected to the element.

Another specific object of the invention is to provide a furnace chamber roof specially shaped to assist in the maintenance of reducing gas envelopes about the heating elements.

A further specific object of the invention is to connect the heating elements in a multi-phase heating circuit in a novel and advantageous manner.

The various features of novelty which characterize my invention are pointed out with particularity in the claims annexed to and forming a part of this specification. For a better understanding of the invention, however, its advantages, and specific objects attained with its use, reference should be had to the accompanying drawing and descriptive matter in which I have illustrated and described a preferred embodiment of the invention.

Of the drawing:

Fig. 1 is a side elevation of a melting furnace partly broken away and in section;

Fig. 2 is a partial section on the line 2—2 of Fig. 1, with parts broken away; and

Fig. 3 is a diagrammatic representation of a furnace heating element and heating circuit arrangement.

The furnace A shown in the drawing comprises walls formed of suitable refractory and heat insulating material and covered by a sheet metal casing B to avoid leakage and enclosing a furnace chamber A', with a hearth A² supporting the metal melted, or other material treated. Extending across the furnace chamber in the upper portion thereof, are a suitable plurality of parallel horizontally disposed electric heating elements, each comprising an elongated resistor body C and end members D connected to the ends of the body C and mounted in the side walls of the furnace.

As shown, each resistor body C is an elongated cylindrical body of carbon in an amorphous form having a relatively high electrical resistance. Each body C is formed with an axial passage C'. I now contemplate that in the ordinary practice of the invention, the heating resistors C employed will be commercially available carbon electrodes which are now manufactured for use in electric arc furnaces. Each end member D is a cylindrical body of graphite which is a much better electrical conductor than amorphous carbon, and is formed with an axial passage D'.

In the preferred construction shown, each resistor body C is connected at each end to the corresponding end member D, by an externally threaded nipple E approximately one half of which is screwed into an internally threaded counterbore or socket C² formed in the body C, while the remainder of the nipple is threaded into an internally threaded counterbore or socket D² formed in the adjacent end of the end member D. Each member D may well be somewhat larger in diameter than the resistor body C, in order that the heating element end member resistance and heat losses may be correspondingly reduced. The nipples E may well be such connector parts, formed of amorphous carbon, as are now in use in connection with furnace electrodes. As

shown, the axial channel C' of each resistor is in communication with the channels D' of the associated end members D through the bores of the corresponding nipples E, said bores, as shown, being of the same diameter as the axial channels.

At its outer end each member D is formed with an internally threaded counterbore D³ to receive a threaded portion of a corresponding contact or terminal member, ordinarily formed of copper. Each of the contact members F at the left hand side of the furnace, as seen in Fig. 2, has an externally threaded inner end portion F' of reduced diameter, which is screwed into the corresponding end member socket D³, so as to normally hold a collar or flange portion F² of the contact members in snug engagement with the outer end of the end member. Each contact member F is formed with an axial passage F³ which communicates with the corresponding end member passage D'. Each member F is formed with a cooling fluid space F⁴, and is formed at the outer end of the element with inlet and outlet ports F⁵ and F⁶ for the passage of a cooling fluid, usually water, into and out of the space F⁴.

The outer surface of the body portion of each contact member is cylindrical and extends away from the furnace wall through a stuffing box comprising a chambered member G mounted on the furnace wall, and an adjustable gland G' extending into the chambered member and adapted to compress packing material G² within the latter. As shown, a gasket G³ of asbestos or the like is interposed between each member G and the adjacent portion of the outer side of the furnace wall. To further reduce the heat transfer to each stuffing box, the adjacent end of the corresponding end member D is advantageously spaced inwardly some distance from the outer side of the furnace, so that a portion of the heat insulating material forming the outer portion of the furnace wall may be interposed between the gasket G³ and the end member D.

At the right hand side of the furnace as seen in Fig. 2, the outer socket D³ of each end member D receives the reduced and externally threaded inner end portion H' of a fluid cooled electric contact or terminal member H, comprising parts H', H², H⁴, H⁵ and H⁶, corresponding to the parts F', F², F⁴, F⁵ and F⁶, respectively, of each terminal part F. Each contact member H, which need not include an axial passage H³, is provided at its outer end with an externally threaded portion H', which is screwed into a socket formed in a corresponding copper jumper or connector I, which has a second socket receiving the connector end portion H⁷, of another heating element, the different heating elements being thus connected in pairs at one side of the furnace.

In the preferred form of the present invention, the different threaded connections by which the parts C, D, E, F and H of each heating element are united to one another and to the connector I, are all threaded in the same direction, so that a suitable torsion device may subject the contact device F of the element to a turning torque in the proper direction to neutralize any tendency of the different threaded connections to loosen up in use, and to maintain sufficient contact pressure between the engaging thread surfaces, and between the abutting ends of the resistor body C and end members D, and between the outer ends of the latter and the contact flanges F² and H, to suitably minimize the corresponding resistance of the joints between the engaging

surfaces. In the simple form illustrated in the drawing, each torsion device comprises a weight J suspended from an arm J' adjustably secured to the corresponding contact F so that the arm may extend in a generally horizontal direction away from the contact.

In accordance with the present invention, a suitable gas is continuously supplied to the bores or axial passages C' and D', of the non-metallic portions of each heating element, through the axial passage F³ in the copper contact or terminal member F, by a corresponding gas supply pipe or hose connection K. The gas thus supplied passes slowly through the pores of the carbon and graphite bodies C, D, and E, to the outer surface of the parts C and D of the element, and passes more rapidly through such joints or cracks as may normally be expected to initially exist, or which may develop from time to time in the operation of a heating element. Such joints or cracks E, will normally be sealed in a comparatively short operating period by carbon cracking out of the gas and depositing in the cracks or joints. The carbon thus deposited not only seals the joints or cracks, but forms a good mechanical and electric conducting bond between the walls of the cracks or joint. While there will be some cracking of the gas flowing through the graphite and carbon pores, the resultant deposit of carbon in the pores will be very much slower than in the first mentioned joints or cracks, which offer sufficient resistance to electric current flow to produce appreciable local increases in heating element temperatures, greatly increasing the cracking action on the gas flowing through the cracks or joints. Under normal operating conditions, carbon will not be deposited in the carbon and graphite pores at a rate rapid enough to prevent the heating element from having an operating life of commercially acceptable length.

The reducing gas which slowly passes outwardly from the bore of each heating element to its outer surface, tends to maintain a reducing atmosphere in the furnace chamber. In order that the furnace chamber atmosphere in immediate proximity to the heating elements may be maintained definitely reducing under conditions in which the general chamber atmosphere may be less definitely reducing, I advantageously shape the roof of the furnace chamber to provide a separate horizontal space or cell L for each heating element in which the upper portion of the element is received, each space or cell L being open at its underside. The cells L may be formed, as shown, in a furnace of satisfactory construction, by providing a plurality of masonry arches M, which alternate along the length of the furnace with the cell spaces L, and which have their ends in abutting relation with the right and left hand furnace walls, as seen in Fig. 2. Each of the arches M is shaped to provide a top portion M' extending horizontally from one side of the furnace to the other and of keystone shape in cross section. The opposite sides M² of each top portion M' diverging downwardly and away from one another, form the abutments for adjacent masonry arch portions N of the furnace roof, each of the arches N forming the top wall, or crown portion, of a corresponding cell or space L. The location of a heating element in its space or cell L, obviously tends to retard the movement away from the heating element, of the reducing gas slowly leaking from its axial passage through the pores of

the carbon and graphite portion of the element.

The continuous introduction into the furnace chamber of a suitable reducing gas supplied to the pores of the heating elements as above described, not only maintains or contributes significantly to the maintenance of the proper furnace atmosphere required for the production of oxygen-free copper, and required for other metallurgical furnace operations, but contributes directly to a desirably long operating life of the heating elements by protecting the latter against contact with oxidizing gases.

As those skilled in the art will understand, the composition of the gas passed into the heating elements may vary with conditions and particularly with the relative availability of different gases suitable for the purpose. As previously indicated, I advantageously use a free cracking gas, such for example, as propane, in an initial joint sealing period of operation, and use under subsequent regular operating conditions, a more stable, but definitely reducing, gas. Ordinarily the latter may well be of a commercially known type practically free from moisture and other objectionable impurities, and of about the following composition.

	Per cent
Carbon monoxide	6
Carbon dioxide	6
Hydrogen	11
Nitrogen	77

In the furnace shown there are six heating elements, connected at one side of the furnace by jumpers I to form three heating units, each including two side by side heating elements and a connecting jumper I. As shown in Fig. 3, the ends remote from the jumper I of the two heating elements of each unit are connected to the terminals of a corresponding individual phase section of a three phase distribution system. Thus, as shown in Fig. 3, the two heating elements of each unit are connected in series with one another and with one of the three separate phase sections of the secondary winding 0 of a transformer, which may be of any conventional type and hence need not be further illustrated or described. It is to be noted, however, that the transformer must in practice serve to reduce the supply voltage, which may well be 10,000 volts or higher, to a secondary voltage of 10 volts or so. Such a small voltage supplies energy at a suitable rate, for example, in a furnace of the type shown, having amorphous carbon heating elements C, which are eight inches in diameter, sixty inches long, and are each formed with an axial passage C' three inches in diameter.

The connection of the heating elements to a multiphase supply circuit in the general manner illustrated in Fig. 3, insures desirable balanced load conditions and simple circuit connections. For an ordinary metal melting or refining furnace, six heating elements of the character described will be adequate to supply heat at the required rate. In the case of a furnace in which more than six heating elements are required, use may be made of two or more sets of six heating elements each, with each set connected to a multiphase supply circuit in the general manner illustrated in Fig. 3. Although the present invention is especially advantageous for use in furnaces employed in melting and refining metals which need to be protected against oxidation by the maintenance of a reducing atmosphere in the furnace chamber, the invention may well

be employed in furnaces used for a wide variety of other purposes.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent is:

1. In a furnace, the combination with the furnace chamber, of electrical heating means therefor comprising a hollow porous resistor of refractory material within said chamber, and means for closing cracks and joints in said hollow resistor comprising means for passing into said hollow resistor a gas including a carbon constituent which cracks at high temperatures and deposits solid carbon thereby formed in said cracks and joints.

2. An electrical furnace heating element comprising two tubular bodies of graphite adapted to be incorporated in opposed walls of a furnace chamber, and a tubular body portion of amorphous carbon adapted to extend across said chamber and in threaded connection at each end with the adjacent end portion, said tubular bodies of graphite having a specific resistance much lower than that of said body portion of amorphous carbon.

3. In a furnace, the combination with the opposing walls of a furnace chamber, of electrical heating elements each having end portions of graphite mounted in said walls and a body portion of amorphous carbon extending across the chamber and each formed with a longitudinal gas channel, and means for supplying a reducing gas to the said channel of each heating element, said end portions of graphite having a specific resistance much lower than that of said body portion of amorphous carbon.

4. The combination with an electric heating element comprising a plurality of conducting sections arranged end to end with threaded connections between the adjacent ends of adjacent sections, all of said connections being threaded in the same direction, means for holding the section at one end of the element against rotation and means for continuously subjecting the section at the other end of the element to a torque in the direction to tighten said threaded connections.

5. An electric heating unit comprising two similar heating elements arranged side by side and each comprising two end portions and an intermediate body portion with a threaded connection between each end of the latter and the adjacent end portion, an element connecting member at one end of the unit, a separate threaded connection between said member and each of the two adjacent element end portions, the said threaded connections being all threaded in the same direction so that all may be maintained tight, by impressing torque on each of the two element end portions remote from said connecting member, and means for continuously impressing torque on each of the two last mentioned element portions in the direction to maintain said threaded connections tight.

6. An electric heating unit comprising two similar heating elements arranged side by side and each comprising end portions of graphite, a body portion of carbon, a threaded connection between each end of the body portion and the corresponding end portion, an element connecting member at one end of the unit, a separate threaded connection between said member and each of the two adjacent element ends, a separate metallic terminal for each element at the end of the latter remote from said connector and a threaded connection between each terminal and the adjacent end portion of the corresponding element, the said threaded connections connecting the end portions of each element to the body portion thereof and to said connecting member and the corresponding terminal being all threaded in the same direction so that the different threaded connections of each element can be maintained tight by a torque impressed on the corresponding terminal, and means for continuously subjecting each of said terminals to a torque to thereby maintain said connections tight.

7. In a furnace, the combination with the opposing walls of a furnace chamber of electric heating elements extending across said chamber and each comprising graphite end portions mounted in the opposing walls of the furnace chamber and a carbon rod extending across the furnace chamber and in threaded engagement at each end with the corresponding end portion, each of said elements being formed with a longitudinal channel and means for closing cracks and joints in each of said elements comprising means for passing into the said longitudinal channel of each element a gas including a carbon constituent which cracks at high temperatures and deposits solid carbon thereby formed in said cracks and joints.

8. In a furnace, the combination with the opposing walls of a furnace chamber, of two side by side electrical heating elements each having end portions of graphite mounted in said walls and a body portion of amorphous carbon extending across the chamber, a threaded connection between each end of the body portion and the corresponding end portion, a connecting member at one side of the furnace chamber, a threaded connection between said member and the adjacent end of each of said elements, a separate metallic terminal for each element at the end of the latter remote from said connector and a threaded connection between said terminal and the adjacent end portion of the element, the said threaded connections connecting the end portions of each element to the body portion thereof, and to the corresponding terminal and connecting member, being all threaded in the same direction, and a torsion device connected to each terminal and subjecting the latter to a torque tending to tighten each of the different threaded connections of the element.

9. In a furnace, the combination with the furnace chamber and its enclosing wall, of an electrical heating resistance unit therefor comprising a hollow porous resistor of amorphous carbon within said chamber, hollow resistor end connections of graphite mounted in the chamber wall and engaging and supporting end portions of said resistor, and means for closing cracks and joints in said hollow resistor comprising means for passing into said hollow resistor a gas including a carbon constituent which cracks at high temperatures and deposits solid carbon thereby formed in said cracks and joints.

10. In the operation of an electrical furnace comprising a hollow electrical heating resistor unit of porous refractory material, the method which consists in passing into said unit a gas under a pressure sufficient to force the gas outwardly through pores, cracks and joints of the unit, and including a carbon constituent which

will crack and passing electrical current through the resistor to heat the walls of joints and cracks therein to a temperature high enough to crack said constituent and thereby cause said joints and cracks to be sealed by carbon cracked out of the gas.

FRANK W. BROOKE.
